UNITED STATES PATENT OFFICE

141,554

DESIGN FOR A ROTARY ACTUATOR FOR MOVABLE PARTS OF AN AIRCRAFT OR THE LIKE

William P. Lear, North Hollywood, Calif., assignor
to Lear, Inc., Piqua, Ohio, a corporation of Illinois

Application October 5, 1944, Serial No. 115,621

Term of patent 14 years

(Cl. D26—5)

To all whom it may concern:

Be it known that I, William P. Lear, a citizen of the United States of America, residing at North Hollywood, in the county of Los Angeles, in the State of California, have invented a new, original, and ornamental Design for a Rotary Actuator for Movable Parts of an Aircraft or the like, of which the following is a specification, reference being had to the accompanying drawings, forming a part thereof.

In the drawings:

Fig. 1 is a top plan view of a rotary actuator for movable parts of an aircraft or the like, illustrating my new design.

Fig. 2 is a side elevational view of the rotary actuator shown in Fig. 1.

Fig. 3 is a left end elevational view of the rotary actuator shown in Figs. 1 and 2.

Fig. 4 is a right end elevational view of the rotary actuator shown in Figs. 1 and 2.

I claim:

The ornamental design for a rotary actuator for movable parts of an aircraft or the like, substantially as shown.

WILLIAM P. LEAR.
